FOOT X-RAY MACHINE

Herman G. Fischer, Chicago, and Howard H. Osborn, Elmwood Park, Ill., assignors, by mesne assignments, to X-Ray Shoe Fitter, Inc., Milwaukee, Wis., a corporation of Wisconsin

Application September 23, 1932, Serial No. 634,550

5 Claims. (Cl. 250—34)

This invention relates to X-ray apparatus for fitting shoes, and has for its object broadly the provision of such an apparatus of simple and improved construction.

5 A principal object of the invention is the provision of an X-ray apparatus for the fitting of shoes, adapted for use in the ordinary shoe retail store and in which the image of the foot within the shoe may be viewed with full protection to the observer against damage from the X-ray. The invention contemplates in this regard construction of the apparatus to permit observance of the foot in the shoe without looking into or toward the X-ray tube or in line with the generated ray and protection against leakage of the generated rays in its cabinet or casing.

Numerous other objects and advantages of the invention will be apparent as it is better understood from the following description, which, when taken in connection with the accompanying drawings, discloses a preferred embodiment thereof.

Referring to the drawings,

Figure 1 is a vertical front-to-back central sectional view through an apparatus embodying the invention;

Fig. 2 is a top plan view thereof;

Fig. 3 is a transverse horizontal section taken substantially on the line 3—3 of Fig. 1; and

Fig. 4 is a wiring diagram showing the electrical connection and parts which are or may be provided.

The X-ray apparatus embodying the present invention, as illustrated on the drawings, comprises a casing generally composed of a bottom 11, side walls 12, back wall 13, a top wall 14, a platform 15, and front wall sections 16, 17 and 18. The platform 15 is provided with a fluorescent screen 21 and is located above the bottom a substantial distance to provide a lower front chamber 19. The front wall part 17 is spaced outwardly so that it overhangs the platform and this front wall part provides an upper front chamber 22 in which is mounted the X-ray tube 23. A suitable closure 24 (of bakelite) is arranged beneath the X-ray tube and above the foot receiving pocket 25.

Beneath the screen 21 is arranged a mirror 26 adapted to reflect the image created upon the screen 21 by the X-ray tube. A second mirror 27 is located rearwardly of the mirror 26 to receive the reflected image and in turn reflect it upwardly to an observation station at the top of the casing. The mirrors 26 and 27 are arranged at

90° to each other and at 45° to the horizontal and vertical.

Reference character 28 indicates an eye piece located at the observation station and through which the wearer of the shoe being fitted may look down upon the mirror 27 and observe the reflection of the image created by the X-ray tube. The eye piece is mounted upon an extensible bellows 29 in order that it may be adjusted to a convenient height. A second sight opening 31 is provided in order that a second person, as a parent of a child or the salesman, may also observe the fit of the shoe as reflected in the mirrors. The space between the sight opening and the mirror 27 is unobstructed and constitutes a viewing well into which none of the rays emanating from the X-ray tube can enter. The sight opening 31 is adapted to be closed by a shutter 32 operable by movement of a hand member 33. Each of the two sight openings are thus located behind the X-ray tube and out of direct line of the generated rays so that observance of the fit of the shoe does not require observation made in line with the rays or toward the generating tube. The casing is preferably lined with lead upon appropriate inner walls as indicated by reference character 40 in order that leakage likely to damage the observer or other persons within the retail store may be prevented.

The controls for the X-ray circuits are located upon the back of the cabinet and are generally indicated on the drawings by reference character 34. The supply of current to the X-ray tube and the several circuits are typically illustrated in Fig. 4. Viewing Fig. 4 reference characters 35 and 36 indicate line wires for supplying current. From the wire 35 and through a fuse 37 connection is made to any one of a number of terminals 38 at one side of a primary 39 of a transformer 41 for supplying current to the filament 42 of the X-ray apparatus. From the primary 39 a wire 43 leads to a switch 44 and from the switch 44 a wire 45 is connected through a fuse 46 with the wire 36.

The switch 44 is adapted to be closed by the swinging switch arm 47 to complete the circuit and the number of coils in the primary 39 is determined by the particular contact 38 connected to the wire 35.

The filament circuit consists of the secondary 48, wire 49 leading to a filament control 51, a wire 52 from the filament control to one side of the filament 42, and a wire 53 back to the secondary 48. A pilot light 54 is or may be provided in parallel with the part of the primary 39

to indicate whether or not current is flowing through the circuit.

The primary of the X-ray creating circuit comprises a wire 55 connected to the primary 39 and 5 to one side of the primary 56 of the transformer 57. From the other side of the primary 56 a wire 58 leads to a terminal 61 at the switch 44. A second terminal on this switch, indicated at 10 62, is connected through a resistance 63 with the wire 58.

When the switch arm 47 is manipulated to establish contact with wire 45 it first engages an idle terminal 64. In this position current is 15 flowing through and heating the filament circuit. Further swinging in a clockwise direction, viewing the drawings, causes the switch to make contact between the terminal 62 and the wire 45 and current then flows through wire 35, wire 55, primary 56, wire 58, resistance 63 to switch arm 20 47 and thence by wire 45 and fuse 46 to line wire 36.

Movement of the switch arm into engagement with the terminal 61 cuts out the resistance 63 and completes a direct circuit for the primary 25 56. A resistance indicated at 65 may be connected with wires 55 and 58 as protection against surge.

The secondary 66 of transformer 57 is connected by a wire 67 to the anode 68 of the X-ray 30 tube. The other side of the secondary 66 passes through a milliammeter 69 and is grounded at 71. A ground 72 is connected to the filament circuit at 73 and a ground 74 is connected to the core of the transformer 57. The several grounds 35 may be electrically connected as indicated by wire 75.

In order to protect the X-ray tube a thermostatic switch 77 is inserted in the line 53 of the filament circuit. A variable resistance 76 is 40 placed across the filament circuit and connected to wires 49 and 53. This resistance acts as a load and may be employed for adjustment of the timing of the thermostatic switch 77.

It is thought that the invention and many of 45 its attendant advantages will be understood from the foregoing description, and it will be apparent that various changes may be made in the form, construction and arrangement of the parts without departing from the spirit and scope of the invention or sacrificing all of its material advantages, the form hereinbefore described being 50 merely a preferred embodiment thereof.

We claim:

1. An X-ray apparatus for use in fitting shoes, 55 which comprises a casing having a platform on which the individual may stand, an X-ray tube in said casing mounted above said platform, and a fluorescent screen mounted in said platform, and means for reflecting an image on said screen for 60 observation.

2. An X-ray apparatus comprising a cabinet having a platform upon which an individual may stand and provided with a foot receiving pocket as part of said platform, in combination with an 65 X-ray tube in said cabinet vertically above said

socket, a fluorescent screen below said pocket, a reflector inclined downwardly from said platform and beneath said screen, and a second reflector inclined upwardly from the first mentioned reflector, said cabinet having above the second reflector an observation station, whereby a foot may be examined without exposure to direct rays from 5 said tube.

3. An X-ray apparatus for use in fitting shoes comprising a casing provided with a sight opening in its upper portion and a reflector in its lower portion positioned to direct rays of light from a lateral source upwardly to the sight opening said casing providing, a platform at one side of the space between the reflector and the sight opening, said platform being adapted to support a person with his weight on the foot to be inspected, an X-ray tube above the platform arranged to direct its rays downwardly through such foot and along a line obliquely divergent from said space, 15 a fluorescent screen in the path of such rays underneath the foot and an image receiving reflector adapted to direct ray-created images laterally to the first mentioned reflector, said casing having extended portions housing the tube and image 20 receiving reflector.

4. An X-ray apparatus for use in fitting shoes comprising a casing provided with a sight opening in its upper portion and a reflector in its lower portion and having the intervening space unobstructed and adapted to serve as a viewing well, 30 said reflector being adapted to direct rays of light from a lateral source upwardly in said well, said casing having a reentrant portion forming a platform at one side of said well adapted to support 35 a person with his weight on the foot to be inspected, an X-ray tube above the platform arranged to direct its rays downwardly through such foot, a fluorescent screen in the path of such rays underneath the platform and a second reflector adapted to direct ray-created images laterally to the first mentioned reflector at an incident angle for reflection to the sight opening, 40 said casing including extended portions housing the X-ray tube, and reflector underneath the 45 platform, and the casing walls below the platform having a ray intercepting lining.

5. An X-ray inspecting apparatus for use in fitting shoes comprising the combination of a casing providing a viewing well having an obliquely placed reflector in its lower portion and flanked at one side of the lower portion of the well by an image receiving reflector adapted to direct light rays to the first mentioned reflector for upward reflection by the latter through the well, a fluoroscopic screen above the image receiving reflector, a portion of said casing being disposed to form a foot support above said screen, an X-ray tube arranged to direct its rays downwardly through the foot support to the screen, portions of said 55 casing being arranged to form a housing for said tube at one side of the upper portion of the well.

HERMAN G. FISCHER.
HOWARD H. OSBORN.
